CLAIM

The ornamental design for “companion escutcheons with touch pads,” as shown and described.

DESCRIPTION

FIG. 1 is a perspective view of a companion escutcheon with touch pad showing our new design;

FIG. 2 is a right side elevational view thereof;

FIG. 3 is a front elevational view thereof;

FIG. 4 is a top plan view thereof;

FIG. 5 is a bottom plan view thereof;

FIG. 6 is a left side elevational view thereof; and,

FIG. 7 is a perspective view thereof, with the article shown in the environmental use.

The broken lines are for illustrative purpose only and form no part of the claimed design.
